UNITED STATES PATENT OFFICE.

EDWIN R. STORM, OF NEW YORK, N. Y.

PRINTING-PLATE HOLDER.

SPECIFICATION forming part of Letters Patent No. 703,676, dated July 1, 1902.

Application filed January 2, 1902. Serial No. 83,126. (No model.)

To all whom it may concern:

Be it known that I, EDWIN R. STORM, a citizen of the United States, residing at New York, in the county of New York and State 5 of New York, have invented a new and useful Printing-Plate Holder, of which the following is a specification.

My invention relates to improvements in holders for printing-plates in which plate-clamps are used in conjunction with a grooved block; and the objects of my invention are, first, to provide a plate-clamp that may be inserted at any point of the groove and be quickly and reliably secured thereto; second, 15 to provide a plate-clamp that will hold the printing-plate to the grooved block when a sufficient number of the plate-clamps are secured in the grooves; third, to provide a plate-clamp that may be quickly removed from the 20 groove without separating its component parts. I attain these objects by means of the devices illustrated in the accompanying drawings, in which—

Figure 1 is a view of a portion of the grooved block with a printing-plate thereon, showing 25 two of the plate-clamps secured in position. Fig. 2 is a sectional view of the block, showing the plate-clamp secured within the groove holding the printing-plate to position, drawn 30 to an enlarged scale. Fig. 3 is a sectional view of the block and plate-clamp, showing the method of entering the plate-clamp in the groove, drawn to an enlarged scale. Fig. 4 is a sectional view of the block and groove, 35 showing the plate-clamp partly in the groove, drawn to an enlarged scale. Fig. 5 is an isometrical view of the face-piece of the plate-clamp, drawn to an enlarged scale. Fig. 6 is an isometrical view of the nut of the plate- 40 clamp, drawn to an enlarged scale. Fig. 7 is an isometrical view of a plate-clamp, drawn to an enlarged scale. Fig. 8 is an end view of a modified plate-clamp in which the sides 12^a 13^a of the portion 6^a are not formed parallel and the nut is held by retaining-grooves 45 in sliding contact with the portion 6^a. Fig. 9 is a side view of the plate-clamp shown in Fig. 8. Fig. 10 is a sectional view of the plate-clamp shown in Fig. 8.

Similar numbers of reference indicate corresponding parts in the several views.

1 indicates the grooved block of my im-

proved plate-holder, which block is of the same construction as now in common use, of any desired size, and consists of a block having grooves 2 of greater width at the lower than at the upper part. 55

The printing-plate 3 is secured to the grooved block 1 by means of the plate-clamps 4. The plate-clamps 4 have each a face-piece 6^a 5, provided with a portion 6, a nut 7, a screw 8, a countersunk hole 9, an edge 10, beveled to fit against and hold the edge of the printing-plate 3 when the plate-clamps 4 are secured in the grooves 2, and a shoulder 11. 65 The portion 6 has one face 12, adapted to fit against the inclined side 2^a of the groove 2, a face 13, adapted to work against the face 14 of the nut 7, a face 15, formed to allow the nut 7 to approach the face 16 when the screw 70 8 is held in the nut, and a face 16, formed to assist in inserting the plate-clamp in the groove and to remove the long sharp edge that would result in prolonging the faces 12 and 15. The portion 6 is recessed at 17 to 75 allow space for the screw 8 when the nut 7 is made to approach the face 16.

The nut 7 is formed with a face 14, adapted to work against the face 13, a face 18, adapted to work against the inclined sides 2^a of the 80 groove 2, two faces 19 and 20, formed parallel with each other and at a distance apart slightly less than the top of the groove 2, so the nut 7 may be easily inserted in the groove or withdrawn therefrom at any point, the 85 thickness of the nut to be somewhat less than the depth of the groove. The nut 7 is provided with the threaded hole 21.

The screw 8, fitted to and adapted to work in the threaded hole 21, has the portion 22 of 90 the head working in the countersunk hole 9 preferably formed as a portion of the surface of a sphere, while the countersunk hole 9 is formed to fit and adapted to receive the spherically-formed portion 22 of the head of 95 the screw 8.

The shoulder 11 is formed to fit in the groove 2 when the plate-clamp is in position on the block 1 and tends to keep the clamp from turning when the screw 8 is turned. 100

The manner of using the plate-clamps is as follows: The face-piece 5 and the nut 7 having been connected by the screw 8 passing through the countersunk hole 9 and working

in the threaded hole 21, the screw 8 is turned until it is nearly withdrawn from the threaded hole 21. The spherically-formed portion 22 of the head of the screw 8 is brought to bear against the surface of the countersunk hole 9, and the nut 7, sliding on the surface 15, is held with its face 14 as near as possible to the face 16 of the portion 6. With the several parts in the positions indicated the 5 nut 7 is inserted at any convenient point in the groove 2, as indicated in Fig. 3. After the nut passes into the groove it is forced to one side by the face 16 entering the groove and working against one edge of it. 10 Continuing the insertion, the nut 7 strikes against the bottom of the groove 2 and is moved by the face 15 far enough to one side to permit the portion 6 to enter the groove 2, with its face 12 working against the inclined 15 side 2' of the groove and its face 13 working against the face 14 of the nut 7. (See Fig. 4.) Pushing the plate-clamp 4 to place, with the face-piece 5 bearing on the top of the block 1 and the beveled edge 10 against the beveled 20 edge of the printing-plate 3 and turning the screw 8 so as to cause it pass further in the threaded hole 21, lifts the nut 7 from the bottom of the groove, causing the face 18 to bear against the inclined face 2' of the groove 2 and the face 14 to bear against the face 13 of the portion 6. The pressure against the face 13 is transmitted through the portion 6 to the face 12, which bears against the inclined face 2' of the groove 2. The inclined faces 2' 2' 25 of the groove 2 being immovable stop the upward movement of the nut 7 and cause it upon the continued turning of the screw to pull and hold the plate-clamp down to the face of the block 1, the portion 6 being forced 30 to slide between the inclined side 2' of the groove and the face 14 of the nut 7. When the turning of the screw 8 has taken up all sliding motion, it forces the nut 7 and the portion 6 in tight frictional contact with the 35 inclined sides 2' 2' of the groove 2, as shown in Fig. 2, thereby locking the plate-clamp immovably upon the block. The beveled edge 10 being held in its desired position against the beveled edge of the printing- 40 plate at the moment of tightening the screw bears against the beveled edge of the printing-plate when the screw is tightened and tends to hold that portion of the printing-plate to the block 1. Inserting a sufficient 45 number of the plate-clamps within the grooves 2, causing them to bear against the beveled edges of the printing-plate, and tightening their individual screws will hold the printing-plate securely to the block 1. 50 When it is desired to remove the plate-clamp 4, the screw 8 is turned until it is nearly withdrawn from the threaded hole 21, the face-piece 5 is lifted, when the portion 6 slides between the inclined side 2' of the groove 2 and the face 14 of the nut 7. The nut 7 is forced by the inclined side 2' of the groove 2 55 to slide along the face 15, permitting the face

16 to slide against the upper edge of the inclined side 2' and the portion 6 to be wholly withdrawn from the groove, when the nut 7, attached by the screw 8 to the face-piece 5, is withdrawn from the groove 2 by the screw 8.

Not wishing to be understood that the face 13 must be parallel to the face 12 I have shown in Fig. 9 a modified form of the plate-clamp, in which the face 13a is inclined to the face 12a and the nut 7a is formed longer than the portion 6a and is provided with the retaining-grooves 23a, to which are fitted the beveled ends 24a of the portion 6a. The beveled ends 24a, working within the retaining-grooves 23a, hold the nut 7a and the portion 6a in sliding contact.

Fig. 8 is an end view of the modified plate-clamp shown in Fig. 9, the screw 8a being shown in dotted lines and given a conical head, as the spherically-formed head is not absolutely essential to the proper working of either form of plate-clamp.

Fig. 10 is a sectional view of the plate-clamp shown in Fig. 9, showing the nut 7a moved to position requisite for entering the plate-clamp in a groove. Because of the retaining-grooves 23a and the face 13a being inclined to the face 12a the face 15 is omitted.

Having described my invention, I claim and desire to secure by Letters Patent—

1. In a holder for printing-plates the combination of a block having grooves adapted to receive and hold one or more plate-clamps, and plate-clamps held in the grooves each of said clamps consisting of a face-piece having a wedge-shaped portion adapted to enter and partly fill the said groove, a nut adapted to be inserted at any point of the groove and act in conjunction with the said portion in the groove to hold the face-piece to the block and a screw connecting said nut and face-piece.

2. In a holder for printing-plates the combination of a block having grooves adapted to receive and hold one or more plate-clamps and plate-clamps held in the grooves each of said clamps consisting of a face-piece having a portion adapted to enter and partly fill the groove, a face on the said portion adapted to fit against the side of the groove, a nut adapted to be inserted at any point of the groove while connected to the face-piece and act in conjunction with the said portion in the groove to hold the face-piece to the block, and a screw connecting said nut and face-piece.

3. In a holder for printing-plates the combination of a block having grooves adapted to receive and hold one or more plate-clamps, and plate-clamps held in the grooves each of said clamps consisting of a face-piece having a portion adapted to enter and partly fill the groove, a nut narrower than the top of the said groove adapted to be inserted in the groove and act in conjunction with the said portion in the groove to hold the face-piece to the block and a screw connecting said nut and face-piece.

4. In a holder for printing-plates the com-

bination of a block having grooves adapted to receive and hold one or more plate-clamps, and plate-clamps held in the grooves, each of said clamps consisting of a face-piece having 5 a portion adapted to enter and partly fill the groove, a nut of a width to permit it to be inserted at any point of the groove and adapted to act in conjunction with the said portion in the groove to hold the face-piece to the block, 10 and a screw having the bearing-surface of the head formed as a portion of the surface of a sphere, connecting said nut and face-piece.

5. In a holder for printing-plates the combination of a block having grooves of greater 15 width at the bottom than at the top and plate-clamps adapted to be held in the grooves, each of said clamps consisting of a face-piece having a portion adapted to enter and fit against one side of the groove, a nut adapted to bear 20 against the other side of the groove and the portion in the groove and act as a wedge in conjunction with the said portion to hold the face-piece to the block and a screw connecting said nut and face-piece.

25 6. In a holder for printing-plates the combination of a block having grooves of greater width at the bottom than at the top and plate-clamps consisting of a face-piece having a countersunk hole therein, a screw passing 30 through the countersunk hole in the face-piece and working in a threaded hole in a nut, and a nut adapted to pass into the groove at its upper part without withdrawing the screw from the said threaded hole, and a projecting 35 portion on the face-piece adapted to be inserted in the groove and prevent the withdrawal of the nut.

7. In a holder for printing-plates the combination of a block having grooves of greater 40 width at the bottom than at the top and plate-clamps having a nut formed to partly fill the groove and adapted to pass into the said groove at its upper part, a face-piece having a portion adapted to enter the groove, force 45 the nut to one side and act in conjunction with the nut to hold the face-piece to the block, and a screw connecting said nut and face-piece.

8. In a holder for printing-plates the combination of a block having grooves of greater 50 width at the bottom than at the top and plate-clamps having a nut formed to partly fill, and fit against one side of, the groove and adapt-

ed to pass into the groove at its upper part, an inclined plane forming one face of the 55 said nut, a face-piece with a portion adapted to enter and fit against one side of the groove, a face on the said portion adapted to fit against the said inclined plane and means as a screw adapted to cause the inclined plane 60 to slide on its corresponding face and force the portion against one side of the groove and the nut against the other side of the groove.

9. In a holder for printing-plates the combination of a block having grooves of greater 65 width at the bottom than at the top and plate-clamps having a face-piece with a holding edge thereon, a portion extending from the face-piece formed to enter and fit against one side of the groove, a nut formed to pass into 70 the groove at its upper part and partly fill the said groove, a face on the said extended portion formed to force the nut to one side in entering the groove, a face on the said nut formed to fit against and slide on the face 75 formed on the said extended portion and a screw connecting the nut and face-piece adapted to bring the nut in coöperation with the extended portion and hold the face-piece to the block.

80 10. In a holder for printing-plates the combination of a block having grooves adapted to receive and hold one or more plate-clamps, and plate-clamps held in the grooves, each of said clamps consisting of a nut formed 85 narrower than the top of the groove, a face-piece having a portion formed to enter the groove supplement the nut and prevent its withdrawal from the groove and means, as a screw, adapted to work in the nut to draw 90 and hold the face-piece to the block.

11. In a holder for printing-plates the combination of a block having grooves adapted to receive and hold one or more plate-clamps, and plate-clamps held in the grooves each of 95 said clamps consisting of a nut narrower than the top of the said grooves and adapted to be inserted at any point of the groove, a face-piece having a portion adapted to enter and hold the nut within the groove, and a 100 screw connecting the nut and face-piece.
